UNITED STATES PATENT OFFICE.

EDWARD JARVIS WINSLOW, OF CHICAGO, ILLINOIS.

PROCESS OF CONSTRUCTING CONTAINING VESSELS.

SPECIFICATION forming part of Letters Patent No. 772,117, dated October 11, 1904.

Application filed April 27, 1903. Serial No. 154,431. (No model.)

To all whom it may concern:

Be it known that I, EDWARD JARVIS WINSLOW, of the city of Chicago, in the county of Cook and State of Illinois, have invented certain new and useful Improvements in Processes of Constructing Containing Vessels; and I do hereby declare that the following is a full, clear, and exact description thereof, reference being had to the accompanying drawings, and to the letters of reference marked thereon, which form a part of this specification.

This invention relates to a process of constructing containing vessels and is directed more particularly to that class of containing vessels made of cement or plastic material.

The article consists of any suitably-shaped vessel (the design varying according to the use to which the vessel is to be put) made of plastic material—such, for example, as cement—in which is embedded a metallic cage having a similar design, the plastic material and the metallic cage forming one solid integral structure or monolith. Where the shape or design of the finished article requires arms, necks, elongated members, or the like, it is sometimes convenient to construct them separately and then unite them to the body of the vessel by cement or the like; but usually, and particularly when employing the apparatus set forth in an application, Serial No. 156,574, filed simultaneously herewith, this will not be necessary, and the entire structure may be made integral and in one continuous operation.

The process of making such vessel embraces the steps of forming a metallic cage of the desired configuration or design over an interior removable core, applying the plastic material to the cage, and after the material is set in removing the core.

All of these and other features of the invention will be fully understood by reference to the accompanying drawings and will be more specifically set forth in the claims appended to this specification.

In said drawings, Figure 1 is a sectional view of a containing vessel embodying my invention, together with a sectional interior form or core used in its construction. Fig. 2 is a perspective view of the same, illustrating

the process of construction thereof. Figs. 3, 4, and 5 are views in vertical section illustrating several steps in the process of constructing the lower part of the vessel. Fig. 6 is a view in perspective of the lower portion of the metal frame or cage, showing the means of joining the bottom to the tubular body thereof.

Referring to the said illustrations, Figs. 1 and 2, A indicates as a whole one style of containing vessel embodying my invention. It is a jar designed for use in railway-yards to be sunk into the ground and be a receptacle of battery-cells for operating switch-signaling devices. Manifestly, however, the vessel may be used for a variety of purposes and be of any other desired shape or configuration required by such use. This vessel consists of a cylindrical body portion *a*, bottom *a'*, and top *a''* and has located upon the top *a''* a tapered rectangular open neck *A'*, through which neck access may be had to the interior of the vessel A. The said bottom *a'*, body portion *a*, top *a''*, and neck *A'* consist of a metallic cage or frame C, corresponding in form with the vessel, and a body of cement or plaster B, in which the said cage or frame is embedded and which forms with said cage the walls of the vessel. Said body of cement is preferably made of practically uniform thickness throughout the walls of the vessel. Said cage in the instance shown is embedded in the cement wall somewhat nearer the exterior than to the interior surface. This, however, is not essential. In the case of a vessel to be buried in the ground and adapted to contain battery-cells or for like uses the greatest strains to which the wall of the vessel is subjected will come upon the exterior thereof, and in that case it will usually be preferable that the cage should be nearer the interior than the exterior surface of the cement wall. In case, however, the vessel is to be so used as to be subject to interior pressure it will commonly be preferable to have the cage nearest the outer surface of the wall.

The metallic cage C consists, as herein shown, of longitudinal and transverse wires *c c'*, which cross each other and are joined at their intersections to form an open-mesh fabric or wire-netting of familiar construction.

I usually purchase such wire fabric in the open market in rolls and cut off a strip or section of such length that when rolled and its edges interlocked a tubular or cylindric wire member 5 or body, as C', will be formed. Such tubular or cylindric member constitutes the cylindric wall or body of the cage C, the longitudinal wires c running vertically and the transverse wires c' running circumferentially or horizontally 10 of the said cylindric wall, as shown. I prefer to employ a wire fabric in which the longitudinal and transverse wires are joined at their intersections by electric welding, although a fabric in which said wires are interwoven and joined by soldering or dipping 15 may be employed.

The bottom C² of the metallic cage C is formed of a piece of a similar wire fabric cut to a shape corresponding with the tubular 20 body of the cage and having the ends c³ of its wires upturned to form a sort of flange and joined to the wires of the said body portion C' by being interlocked or intertwined with the wires of the latter. As a preferred construction 25 the ends c³ referred to are carried over the lowermost transverse wire c' of the body portion C' and so far as possible twisted about the vertical wires c above said transverse wire. It will be understood that while 30 the wires c c' are secured together at their several intersections by electric welding, soldering, or dipping the wire ends c³ need only be secured to said wires c c' merely by wrapping or twisting, although there will be no 35 objection to said welding or soldering of the wire ends c³ of the wires c c' except the expense thereof. The top C³ of the metallic cage C is similarly made of a piece of wire fabric cut to conform to the shape of the 40 tubular body of the cage and having its wire ends c⁴ turned downwardly and secured to the wires c c' in the same manner as before described in connection with the bottom C².

When the wire frame of the neck A' is made 45 of rectangular form, as in the instance shown, two opposite sides of the neck will preferably be formed by cutting two parallel slits in the top C³ and making a central transverse cut between said slits to form two flaps C⁴ C⁴, 50 which are bent upwardly or outwardly from the plane of the top. Separate end pieces C⁵ C⁵ will then be shaped to fit at their bottom and side edges to the side edges of the opening in the top and to the side margins of the 55 turned-up flaps, the inserted pieces being joined to the edges of the top and the side edges of the flaps C⁴ C⁴ by interlocking or twisting the ends meeting of the wires with each other.

60 The neck of the vessel illustrated is provided with an inwardly-directed flange b, forming an outwardly-facing shoulder b' within the neck for the support of an interior cover or lid for the vessel. As herein shown 65 the said flange is located in the same horizon-

tal plane with the top wall a² of the vessel and constitutes an inward extension thereof. When the said flange b is thus located, the wire fabric at the intersection of the neck with the top C³ of the cage will preferably be 70 extended into said flange. For this purpose the opening in the top C³ is made smaller than the lower part of the neck, and the wires which run from the top upwardly through the flaps C⁴ are bent outwardly over the top 75 and then upwardly, so as to form folds c⁵, while the upright wires c⁶ of the inserted pieces C⁵ are attached at their lower ends to the wires of the top at points outside of the opening in the top, the same being herein 80 shown as attached to wires c⁷, which are parallel with and exterior to the wires which form the margins of said opening.

The vessel illustrated and described has great strength and durability, the metallic 85 cage forming a strong and rigid frame, to which the cement or plastic material is firmly joined.

Having now described the construction of the containing vessel, I will proceed to describe 90 the process by which it is made.

I first apply the fabric which is to constitute the tubular body C' of the cage around an interior removable core E, attaching the fabric temporarily to the core, but making 95 the tubular body sufficiently larger than the core to leave a space between them for the plaster or cement which is to form the inner part of the vessel-wall. I then attach the metal-fabric bottom C² to the tubular body 100 by joining the wire ends c³ of said bottom to the wires c c' of the tubular body, as above described. I then apply to a suitable horizontal table or platform D a layer of plaster or cement thick enough and of proper size to 105 form the bottom wall of the vessel. I then suspend the core E, with the tubular body C' of the cage and the attached bottom C² thereon, over the said layer of cement, as seen in Fig. 3. The said tubular body of the cage is 110 then loosened from the core, so as to permit said body and the bottom C² to drop and rest upon the layer of cement. The said bottom of the cage is then pressed downwardly into the cement until properly embedded therein, 115 this being done while the cement is still so soft as to permit the wires to easily sink or be forced into the mass or layer. In order to insure that the wire-fabric bottom C² shall be suitably located in the cement layer, I 120 place in the cement layer beneath the margins of the bottom a number of spacing-blocks d, as seen in Fig. 3. Said spacing-blocks rest on the platform and are adapted to support the edges of the bottom and all 125 parts thereof at desired distance from or above the said platform. Such spacing-blocks are preferably made of cement, so that they will themselves form part of the bottom wall when the latter hardens. The said spac- 130

ing-blocks will of course be of such thickness as to correspond with the thickness of the cement exterior to the wire cage in the finished article. After the bottom C^2 of the 5 cage has been thus embedded in the cement layer resting on the platform, as shown in Fig. 4, the core D is lowered until its lower edge reaches a point just above the top of the cement layer and supports it in this 10 position. To insure that the lower edge of the core shall be supported at the proper distance above the bottom C^2 of the cage, I place other spacing-blocks, d' , in the cement layer around the upper surface of the bottom member 15 C^2 and inside of the lower edge of the cage C, locating said blocks so as to come beneath the lower edge of the core E. Said spacing-blocks d' are placed in the cement layer when the core is still in its elevated position, as seen 20 in Fig. 4. These spacing-blocks are made of such thickness as to come slightly above the level of the top of the cement layer when they rest upon the bottom member C^2 , so that when the core is lowered and rests upon such spacing-blocks the latter will support the edge of 25 the core slightly above the level of the top surface of the cement layer. It will of course be understood that the purpose of the spacing-blocks d' is to prevent the sinking of the lower 30 edge of the core into the unhardened layer of cement which is to form the bottom wall of the vessel. Said blocks d' will also be preferably made of cement, so that they will form part of the bottom wall of the finished vessel. 35 The core E after being so lowered is correctly located upon the spacing-blocks d' and centered within the tubular body C' of the cage, as seen in Fig. 5. The top C^3 of the cage is then placed in position and secured at its margin 40 to the tubular body C', other spacing-blocks d^2 being placed between the top of the core and the said top C^3 , so that the latter will be held at a distance above the top of the core equal to the thickness of the cement to be applied 45 inside of the said top C^3 . The parts will then be in condition for the application to the cage of the plaster or cement which is to form the side wall, top, and neck of the vessel. The application of the cement to the tubular body 50 of the cage is begun at the lower edge thereof, so as to form an upward continuation of the cement layer resting on the platform D, it being of course understood that the plastic material is applied from the outside of the metallic cage and is pressed through the open 55 spaces thereof and against the core, the exterior surface of the core conforming to the desired interior shape of the finished vessel. During the application of the cement to the tubular body portion of the cage the latter is held 60 by suitable means at a uniform distance from the surface of the core. The means used for this purpose may conveniently consist of wedges d^3 d^3 , interposed between the circumferential wires C' of the cage and the outer

surface of the core. Conveniently a set of such wedges will be applied to one of the circumferential wires C' near the bottom of the vessel before the application of the plaster begins, and when the plaster has been applied 70 nearly to the level of the set of wedges so located the wedges are removed and inserted behind another one of the circumferential wires at a higher elevation and the application of the plaster continued until the wedges are 75 again reached. The same operation may be repeated until the side wall of the vessel is completed. The top wall will then be finished, spacing-blocks d^2 in this instance serving to support the top of the cage while the plaster 80 is being applied. These blocks may be removed through the meshes of the cage as the work progresses; but if the blocks are made of cement they may remain in place and will form part of the finished top wall. From the 85 above it follows that the mass or body of cement forming the bottom, sides, and top will be in a single piece or integral and that the finished vessel will be monolithic.

To facilitate the removal of the core E, it 90 will be made in sections detachably bolted or secured together, the parts of the core being removed singly through the opening in the head or neck.

I claim as my invention—

1. The process of constructing a vessel having a restricted opening in its top, the same consisting in first surrounding by the lower part of a metallic cage, a sectional or collapsible core, the exterior of which is of the desired interior shape of the vessel then suspending the core together with the lower part of the cage over a layer of plastic material, applied to a horizontal surface or platform then lowering the lower part of the cage, until the bottom wall thereof is embedded in said layer of plastic material, then attaching to the said lower part of the cage the top wall thereof over the said core, then applying to the sides and top of the core a layer of plastic material, to form a continuation of the layer on said platform and of sufficient thickness to cover the cage, then allowing the plastic material to set or harden and finally removing the core through the restricted opening; the 100 bottom, sides and top of the vessel being monolithic. 105

2. The process of constructing a vessel having a restricted opening in its top, the same consisting in surrounding by a metallic cage a 120 sectional or collapsible core the exterior of which is of the desired interior shape of the vessel, embedding the bottom of the cage in a layer of the plastic material applied to a horizontal supporting surface or platform, applying to the top and sides of the core a layer 125 of plastic material of sufficient thickness to cover the cage, then permitting the plastic material to set or harden and finally removing the core through the restricted opening; the 130

bottom, sides and top of the vessel being monolithic and being formed in one continuous operation before the plastic material has set or hardened.

5 3. The process of constructing a vessel having a restricted opening in its top, the same consisting in first forming the lower part of a metallic cage, then embedding the bottom wall of the cage in a layer of plastic material 10 applied to a horizontal surface or platform, then locating within the said lower part of the metallic cage a sectional or collapsible core, the exterior of which is of the desired interior size and shape of the vessel, then applying and securing a top wall to said cage over 15 the core, then applying to the sides and top of the core, a layer of plastic material of suf-

ficient thickness to cover the sides and top of the cage, then allowing the plastic material to set or harden and finally removing the core 20 through the restricted opening; the bottom, sides and top of the vessel being integral or monolithic and being formed in one continuous operation before the plastic material has set or hardened.

25 In testimony that I claim the foregoing as my invention I affix my signature, in presence of two witnesses, this 13th day of April, A. D. 1903.

EDWARD JARVIS WINSLOW.
